UNITED STATES PATENT OFFICE.

JOSEPH A. LITTLE, OF CHICAGO, ILLINOIS.

DEVICE FOR MEASURING THE LENGTH OF BOOTS AND SHOES.

1,279,560.

Specification of Letters Patent. Patented Sept. 24, 1918.

Application filed March 17, 1915. Serial No. 14,945.

To all whom it may concern:

Be it known that I, JOSEPH A. LITTLE, a citizen of the United States, residing at Chicago, in the county of Cook and State of Illinois, have invented certain new and useful Improvements in Devices for Measuring the Length of Boots and Shoes, of which the following is a specification.

The object of my invention is to provide a device for accurately measuring the inside length of boots and shoes.

As is well understood in the shoe trade, the indications of size placed on boots and shoes by the manufacturers are quite frequently incorrect. This is the cause of very considerable inconvenience and expense, particularly where the goods are sold to customers at a distance on mail orders. In the case of a mail order house doing a large business in this line, the cost of making exchanges due to the inaccurate marking of sizes on the boots and shoes by the manufacturer, may be very considerable. Besides this, the good will of a customer is likely to be impaired if he receives an ill fitting shoe.

My invention provides a simple device whereby the inside length of a boot or shoe may be very readily and conveniently measured so that the seller may be perfectly certain that a customer will get exactly the size which he has ordered. The length sizes of shoes are, of course, standard for all makes. The difficulty arises from the fact that through carelessness, or for other reasons, the size marked on the boot or shoe is not always accurate. This is especially true in regard to extra size shoes, such as men's twelve size and ladies' nine size shoes. Many manufacturers do not have these extra size lasts so they make the ladies' nine size on an eight last and the men's twelve size on an eleven last.

The invention is illustrated, in a preferred embodiment, in the accompanying drawing, wherein—

Figure 1 is a view in elevation of a shoe with the length measuring device of my invention shown as applied thereto.

Fig. 2 is a view, in perspective, of the heel piece of the measuring device.

Fig. 3 is a similar view of the toe piece, and

Fig. 4 is a sectional view taken on line 4—4 of Fig. 1.

Referring to the drawing, the heel piece

consists of two metal plates 10 and 11, secured together in any suitable manner, for example, by screws 12. The plate 10 is formed with a curved slot 13 to receive the toe piece 14. The heel piece is preferably formed with a curved, bulging portion 15 which fits against the counter of the shoe. The slot 13 for the toe piece 14 is located preferably in the straight shank portion 16 above the bulging part. The toe piece is preferably made of a relatively thin strip of metal which is curved in a plane normal to the plane of the sole of the shoe having reference to the position which the device assumes when in use. The forward end 17 of the toe piece is shaped so that it will fit closely into the toe of the shoe. The other end of the toe piece is provided with a graduated scale 18, the graduations of which are read in the preferred arrangement shown in the drawing, on the rear edge of the shank portion 16 of the heel piece and are accurately calculated to indicate the linear distance between the extreme points 80 on the toe and heel pieces. Preferably the lower edge of the heel piece is formed with a pointed prong 19 for the purpose of accurately positioning the device in the shoe during the measuring operation.

The device is also provided preferably with means for rigidly connecting the toe piece to the heel piece. For example, the heel piece may be provided with a set screw 20 to bear against the measuring strip or toe piece 14. Thus, if it is not convenient to read the scale with the device in the boot or shoe, as may be the case in measuring a boot having a high top, the parts of the device may be locked together by the set screw and the device removed from the boot. The curved or bulged configuration of the lower part of the heel piece and the curvature of the toe piece or measuring strip makes this possible.

While I have described my invention in a preferred embodiment, I realize that it is quite possible to modify the device without departure from the principles of the invention, and I, therefore, do not wish to be understood as limiting the invention to the details of construction described and shown, except so far as the claims are specifically so limited. In the claims I have used the word "shoe" for want of a generic term covering boots, shoes, slippers, overshoes and the like. It will be obvious that the device

might be used for measuring the length of any article of the general class of footwear.

I claim:

1. A device for measuring the inside length of a shoe comprising a heel piece adapted to fit in substantially upright position in the heel portion of the shoe against the counter of the shoe, formed with a shank and a rearwardly bulging portion below the shank, and a toe piece engaged with and guided by the heel piece so as to be movable only in the direction of its length upon the shank portion of the heel piece, curved downwardly so as to extend into the toe of the shoe to the extremity thereof and so that the other extremity will lie between said shank and the back portion of the shoe, and provided with a graduated scale readable upon a fixed point on said shank.
2. A device for measuring the inside length of a shoe, comprising a heel piece adapted to fit into the heel of a shoe and formed with a slot; a toe piece curved in a plane normal to the plane of the sole of the shoe, slidably arranged in said slot and provided with a graduated scale readable upon a fixed point on the heel piece to indicate the length measured by the heel and toe pieces.
3. A device for measuring the inside length of a shoe, comprising a heel piece formed

with a shank and a rearwardly bulging portion below the shank, the shank having a slot extending therethrough, a toe piece adapted to slide through said slot and provided with a graduated scale adapted to be read upon a fixed point on said shank, and means for fastening said toe piece rigidly to said heel piece.

4. A device for measuring the inside length of a shoe, comprising a heel piece, the upper portion of which forms a relatively straight shank, the lower portion of which is bulged out rearwardly so as to fit the counter of the shoe, the shank being formed with a curved slot and the lower edge of the heel piece provided with a prong, a strip of metal curved in a plane normal to the plane of the sole of the shoe slideable through said slot, formed at its forward end to fit into the toe of the shoe and provided with a graduated scale, the graduations of which when read in connection with a fixed point on the heel piece indicate the lineal distance measured by said device; and a set screw for fastening said strip rigidly to said heel piece.
